UNITED STATES PATENT OFFICE.

CHARLES R. NALLE, OF WICHITA FALLS, TEXAS.

FASTENING DEVICE.

Application filed September 29, 1923. Serial No. 665,735.

To all whom it may concern:

Be it known that I, CHARLES R. NALLE, citizen of the United States of America, residing at Wichita Falls, in the county of 5 Wichita and State of Texas, have invented certain new and useful Improvements in Fastening Devices (Case B), of which the following is a specification.

The present invention resides in the provision of means for securing wires and particularly fence wires to concrete or metallic posts and consists in the provision of wedges for bending or clinching the conventional staples to spread their extremities and effect a binding engagement with the post the staples straddling the wires in the usual manner.

More specifically the device includes a post formed with suitably spaced slots or 20 openings in which are arranged detachable metallic wedges and staples for engaging wire strands which are expanded by contact with the wedge faces and caused to spread or penetrate beyond the slots or openings for 25 locking engagement with the post.

This device also includes a wedge structure formed with a cross-head to limit the movement of the wedge within the opening and also to act as a seat for the wire strand 30 at its point of engagement with the staple thereby insuring a firm and rigid connection.

Other features will more clearly herein-after appear by reference to the accompanying drawings forming a part of this invention and wherein like numerals of reference 35 designate corresponding parts throughout the several views, in which:

Figure 1 is a front elevation of a post 40 constructed in accordance with the present invention showing some of the strands broken away.

Figure 2 is a side elevation of a post parts being broken away to show the arrangement 45 within the slots.

Figure 3 is a section through one of the openings showing the present device in position before the staple is driven into engagement with the wedge.

50 Figure 4 is a similar view showing the staple in position after engagement with the wedge.

Figure 5 is a top plan view of the wedge or expander, and

Figure 6 is a sectional view showing a modified form of the wedge designed for use in connection with hollow metallic posts.

Referring now to the detailed construction, I have shown in Figures 1 and 2 a concrete post construction provided with vertically aligned elongated slots suitably spaced to produce the desired distance between strands. These slots indicated by reference character 1 are of any desired depth dependent upon the type of fastener to be utilized as will more clearly hereinafter appear.

Arranged within the slots are the staple expanders each comprising the flat wedge shaped body 2, shank 3 and head 4. The body portion 2 is of suitable dimension to fit snugly within the slot and tapers gradually inward toward the shank portion 3 which latter is substantially square in cross section. The head 4 may be formed by twisting the shank portion 3 so that the arms 5 and 6 extend at right angles to the flattened wedge-shaped body 2. The shank need not be twisted in the usual sense of the word, but may be a straight connection between the body and head, which are at an angle to each other, and the term twisted is used in a relative sense. These arms 5 and 6 extend laterally of the body a sufficient distance to permit a substantial engagement with the outer face of the post to provide a suitable support for the body 2 during the seating of the staple 7. This staple 7 may be of the conventional U-shaped type and the extremities of the prongs are sharpened as at 9 by being beveled on their inner faces, the angle of the bevel being in substance identical with the angle of the wedge-shaped body 2 to permit proper engagement between these parts.

In Figures 3 and 4 there is shown in detail a staple expander arranged in a suitable slot in a concrete post. In the former figure, the staple 7 is shown straddling the wire strand 10 and the beveled extremities of the staple resting against the tapering faces of the wedge. In the latter figure the staple has been driven home and the staple extremities are shown penetrating the walls of the slot, being forced into such walls by the tapered faces of the expander. Particular attention is called to the fact that the wire 10 after the staple has been driven

into position, is firmly clamped between the latter and the outer face of the head 4 and due to the width of this head is no way bent or twisted so as to injure same.

- 5 In Figure 6 the present device is shown applied to a hollow metallic post. This post indicated by reference character 11 is formed with suitably spaced openings 12 which correspond to the slots in the concrete post 10 heretofore described. In connection with this type of post it has been found advisable to alter slightly the construction of the staple expander by providing the lips 14 the inner faces of which are substantially transverse to the longitudinal axis of the body. These lips 14 tend to direct the staple extremities outward against the inner wall of the hollow post body and clinch the same thereagainst.
- 15 20 In use with either type of post the wedge-shaped body of the expander is inserted in the slot or opening until the lateral arms 5 and 6 engage the outer face of the post. These arms, it is obvious, prevent the loss or displacement of the expander and retain the latter in accessible position at all time. After inserting the expander the staple is caused to straddle the wire and the extremities of the staple are inserted in the slot or opening 25 30 to cause the beveled faces of the latter to engage the tapered faces of the wedge. When in this position, which is clearly shown in Figure 3, the parts are all in readiness for the seating of the staple which is accomplished by a suitable tool. In the instance of a concrete post the staple then assumes the position shown in Figure 4 or in case of a hollow metal post the position shown in 35

Figure 6, binding the wire securely against the head.

40 By a careful examination of this invention it will be obvious that while the substance of the device is illustrated by the accompanying drawings and specifications numerous changes may be made in the details of construction and arrangement of parts without departing from the spirit of the invention.

45 The staple expanders may be made by twisting the head 4 at right angles to the body 2 or by casting or drop forging.

What I claim as new and useful and desire to secure by Letters Patent, is:—

1. A wire fastener element comprising an integral structure and including a body portion formed with integral inclined faces, a head portion including laterally extending arms, and a reduced shank portion between the body and head portions, said shank being relatively twisted to arrange said arms at an angle to said body portion.

60 2. In combination with a post formed with an opening, means for securing a wire across said opening including a staple for engaging said wire, an expander comprising a body portion arranged in said opening and formed with inwardly inclined faces, a relatively twisted shank portion, and a head portion comprising lateral transverse arms for engaging the outer faces of said post, said staple being adapted to straddle said 65 head to clamp the wire thereto, and the extremities of said staple engaging the inclined faces of said expander and penetrating beyond the walls of said opening.

In testimony whereof I affix my signature.
CHARLES R. NALLE.
